CLAIM

The ornamental design for a lighting fixture, as shown and described.

DESCRIPTION

FIG. 1 is a bottom perspective view of a lighting fixture depicting a new design;

FIG. 2 is a top perspective view thereof;

FIG. 3 is a front elevation view thereof;

FIG. 4 is a back elevation view thereof;

FIG. 5 is a left elevation view thereof;

FIG. 6 is a right elevation view thereof;

FIG. 7 is a bottom plan view thereof; and,

FIG. 8 is a top plan view thereof.

The broken line disclosures in the views represent portions of the lighting fixture that form no part of the claimed design.

The downrod is shown with a symbolic break in its length. The appearance of any portion of the downrod between the jagged broken lines forms no part of the claimed design.
